REMOTE CUSTOMER BANKING TERMINAL

Wolfgang R. Stieber, River Vale, N.J., assignor to The
Mosler Safe Company, Hamilton, Ohio

Filed Nov. 24, 1971, Ser. No. 202,073

Term of patent 14 years

Int. Cl. D6—04

U.S. Cl. D69—1

Fig. 1

FIG. 1 is a front elevational view of a remote customer banking terminal showing my new design;

FIG. 2 is a side elevational view of one side thereof, on a slightly reduced scale, the opposite side thereof being identical thereto;

FIG. 3 is a rear elevational view thereof;

FIG. 4 is a top plan view thereof; and

FIG. 5 is a bottom plan view thereof.

I claim:

The ornamental design for a remote customer banking terminal, substantially as shown and described.
